(57) **CLAIM**

The ornamental design for a dry erase board, as shown and described.

DESCRIPTION

FIG. 1 is a perspective view of a dry erase board showing my new design.

FIG. 2 is a front view of the dry erase board shown in FIG. 1.

FIG. 3 is a rear view of the dry erase board shown in FIG. 1.

FIG. 4 is a right side view of the dry erase board shown in FIG. 1.

FIG. 5 is a left side view of the dry erase board shown in FIG. 1.

FIG. 6 is a top view of the dry erase board shown in FIG. 1; and,

FIG. 7 is a bottom view of the dry erase board shown in FIG. 1.

The broken lines contained herein illustrate portions of the dry erase board that form no part of the claimed design.
